REMOTE CONTROL DEVICE FOR RADIO-
RECEIVERS

Adolph A. Thomas, New York, N. Y.

Application October 26, 1929, Serial No. 402,571

36 Claims. (Cl. 250—20)

My invention relates to radio receivers, and its object is to provide a simple device for tuning a receiver from a distance. For this purpose I utilize a small control box having a suitable knob or button which operates a pivoted switch arm arranged to engage a series of contacts. These contacts represent certain stations, and an indicator movable with the switch arm enables the operator to select the station wanted. The control box is electrically connected to the receiver for controlling an electric motor which drives the tuning shaft at properly reduced speed in alternately opposite directions. In a preferred form of my invention, the tuning shaft carries a contact arm movable over a series of radially arranged contacts which are connected to the selector contacts in the control box. To bring in a desired station, a person turns the knob or other finger piece on the control box until the indicator points to that station. The finger piece (or a separate button) is then pushed down, whereby the necessary circuits are automatically closed to operate the tuning shaft until the wanted station is in tune. When that occurs, the contact arm on the tuning shaft closes a circuit to energize a switch-operating coil which opens the motor circuit, so that the shaft remains in tuning position.

The control box may have a signal lamp which lights up when the tuning shaft stops, whereupon the operator lets go of the switch-closing finger piece. I may provide switch connections in the box for keeping the loudspeaker silent during the tuning operation. When the control knob or button is released, the loudspeaker is automatically rendered operative. In one embodiment of my invention, the control box has a single knob for rotating the selector arm and closing the motor circuit. The latter function is accomplished by mounting the knob like a push button capable of axial movement in addition to its rotary movement. In that case the switch arm is normally spaced from the contacts and is turned without engaging them. When the knob is pushed down after a station has been selected, the switch arm is moved into engagement with the contact representing the station, and at the same time the motor switch is closed. I may, however, close the motor switch by a separate push button preferably mounted in the center of the rotary knob. That construction eliminates the necessity of mounting the rotary knob for axial movement, and the selector arm may therefore engage the contacts during its rotary movement. In a less simple form of my invention,

the rotary switch arm and associated contacts in the radio receiver for stopping the shaft in selected tuning position may be replaced by a series of rotary disks provided with contact switches arranged radially to represent certain stations.

The novel features and practical advantages of my invention will be understood from a description of the accompanying drawings, in which—

Fig. 1 shows a top view of a preferred form of my new control box;

Fig. 2 is a section on line 2—2 of Fig. 1;

Fig. 3 represents an inside plan view on line 3—3 of Fig. 2;

Fig. 4 is a fragmentary detail view of a switch in the control box;

Fig. 5 is a section on line 5—5 of Fig. 4;

Fig. 6 is an enlarged section through the insulating base of the control box to show the mounting of certain switch contacts;

Fig. 6a is a section on line 6a—6a of Fig. 2;

Fig. 7 shows a sectional detail of the lamp support in the control box;

Fig. 8 is a side view through a radio receiver embodying certain features of my invention, some parts being sectioned for clearness;

an arc to select the desired station, Fig. 23 being an outer plan view, Fig. 24 a side section on line 24-24 of Fig. 25, and Fig. 25 a plan section on line 25-25 of Fig. 24; and

5 Fig. 26 shows a detail in section on line 26-26 of Fig. 24.

I shall describe first the apparatus shown in Figs. 1-13. The mechanism for controlling the position of the tuning shaft in the radio receiver 10 is housed in a small casing 10, which is here shown as a flat cylindrical box consisting of an insulated base 12 and a cup-shaped body 13 removably secured to the base by screws 14 or otherwise. The base 12 can be molded of bakelite or other suitable insulating composition, and the casing part 13 is easily made of spun sheet metal or shaped of fiber, hard rubber, pulp, celluloid, and the like. If desired, the top plate or cover 15 of box 10 may be made as a separately removable part. A rotary hand knob 16 projects through an opening 17 in the top of box 10 and carries a pointer 18 arranged to move over a scale 19, which in this instance represents ten selected broadcasting stations identified for convenience by the letters 20 A-K. A push button 20 extending through an axial opening in knob 16 is adapted to close the necessary circuits for operating the tuning shaft after the pointer 18 has been moved to the desired station on indicator 19. A knob 21 is adapted to control the volume of reproduction, and a switch member 22 throws the radio receiver into and out of operation. The outline 23 in Fig. 2 represents any practical form of on-and-off switch operated by the finger piece 22. Likewise, the outline 24 in the same figure is intended to indicate any practical device for regulating the volume of the loudspeaker by turning the knob 21. This will be understood without further description.

40 The insulated base 12 of control box 10 is provided with a semi-circular flange or bridge 25, which may be molded integral with the base. The bridge 25 has a series of slots 26 in which contact pieces 27 are inserted in a tight fit, so that they 45 remain fixed without additional fastening means, although such may be used if desired. The contacts 27 may be cut from strips or sheets of brass or other good conducting metal. As seen in Figs. 2 and 6, the top edges of contacts 27 are slightly 50 below the top surface 28 of bridge 25, and the open ends of slots 26 are widened at 29 for a purpose that will presently be explained. While this 55 particular mounting of the contacts 27 is not absolutely necessary, it has practical advantages. To permit the easy attachment of conductors to the insulated contacts 27, these may be provided with extensions 30 having perforations 31 or other means for connecting a wire. The radial arrangement of contacts 27 correspond to the 60 position of the radial indicator lines 19 on top of box 10. In the device as prepared for the market, the contacts 27 may be arranged equidistantly, so that the scale markings 19 are uniformly spaced to improve the appearance of 65 the box. The bridge 25 has a lateral extension or shelf 32 to the underside of which is secured a contact strip 33 of brass or other suitable metal. Screws 34 or the like may be used for attaching the contact strip 33 to shelf 32. A semi-circular projection 35 on base 12 supports a contact strip 36, which may be attached by screws or otherwise. All the wiring that goes into box 10 is contained in a cable 36' which passes through a slot 70 13' of casing 13, so that all electrical connections

may be made before the casing is inserted over base 12.

The rotary knob 16 has a tubular extension or sleeve 37 in which the push button 20 is slidably mounted. The members 16 and 37 may be molded as a single piece of insulating material. A lock nut 38 screwed on sleeve 37 prevents axial movement of the sleeve without interfering with the free rotation of knob 16. The push button 20 carries a cross-pin 39 arranged to engage at its 10 projecting ends in a pair of axial slots 40 in sleeve 37, whereby the push button is locked to knob 16 for rotary movement therewith. At the same time, the push button 20 is free to be depressed in any position of pointer 18. The push button 15 20 is connected at its lower end to the top of an insulating block 42. For convenience of manufacture, the parts 20 and 42 may be cast or molded as one piece, preferably of insulating material. A switch arm 43 is provided with an annular base 44, which fits over the push button 20 and is secured to the top of part 42 by screws 45 or otherwise. One of these screws may be used as a binding post for connecting a conductor to switch arm 43, which is preferably made of spring brass or similar material. The insulating block 42 has a recess 46 for receiving a coil spring 47. The base 12 may be provided with a recess 48 in which the lower end of spring 47 is seated against lateral displacement. The spring 30 47 tends to expand and normally holds the push button 20 and all connected parts in raised position. The sleeve 37 forms a guide and bearing for the push button. The lower end of insulating block 42 is provided with a pair of lateral projections or flanges 49 and 50, which carry two switch arms 51 and 52 respectively. These arms are attached to the flanges by screws or bolts 53, which may also be used as binding posts for conductors. The three switch arms 43, 51 and 52 are 40 preferably formed at their free ends with a nose or lateral offset 54 for the purpose of making good electrical contact in operative position.

Referring to Fig. 2, it is seen that, when the movable parts are in normal raised position under the action of coil spring 47, the arm 43 is above the bridge member 25 and the arm 51 is above the contact strip 36. At the same time, the switch arm 52 is held in pressure engagement with the underside of contact strip 33. When the button 20 is pushed down, the switch arm 43 is moved into pressure engagement with one of the insulated contacts 27, and the switch arm 51 engages the fixed contact strip 33. In the down position of button 20, the third switch arm 52 is out of engagement with contact strip 33. As previously explained, the button 20 is not pushed down until after the pointer 18 has been rotated to the desired indicating position. Since the contacts 27 are in alignment with the indicator lines 19 on the top of box 10, it follows that the switch arm 43 will always engage the particular contact 27 that represents the station indicated by pointer 18. Referring to Fig. 2, it will be seen that the bevelled recess at the top of each contact 65 27 will guide the nose 54 of switch arm 43 into proper engagement with the contact. This means that, even if the pointer 18 should be slightly out of alignment with the indicator mark 19 of the selected station, the switch arm 43 will 70 be guided into proper contact position by the bevelled recess 29. When the knob 16 is rotated, the insulating block 42 and the three switch arms 43, 51 and 52 carried thereby are rotated as a single member. The stationary contact strips 33 75

and 36 are of such extent as to cover the full range of movement of knob 16.

The insulating base 12 of control box 10 has a bracket 55 which carries a socket 56 for receiving the base of a small signal lamp 57. The bracket 55 may be an integral projection of base 12 if the latter is cast or molded. A spring contact 58 secured to bracket 55 engages the central contact of lamp 57. The light from lamp 57 shines through a lens or other transparent member 59, which is held in a ring 60. The top of box 10 carries a screw-threaded shell 61 adapted to receive a screw-threaded projection 62 which is attached to ring 60 or forms an integral extension thereof. The projection 62 terminates in spring fingers 63 adapted to grip the lamp 57. This construction provides a simple means for inserting the lamp into box 10 or removing it when necessary. To insert the lamp 57, it is only necessary to force the bulb between the spring fingers 63. The extension 62 is then screwed into the shell 61 by turning the outer ring 60, which is supposed to be knurled at the edge for easy manipulation. When the ring 60 is turned in, the lamp 57 turns with it and is screwed into socket 56. When the ring 60 is unscrewed, the lamp 57 is turned out of its socket at the same time.

I shall now describe Figs. 8-12, which show the mechanism in the radio receiver for operating the tuning shaft in accordance with the position of pointer 18 on the control box 10. The tuning shaft 64 extends at right angles to the front panel 65 of the receiver and is supported by brackets 66 and 67, which are rigidly mounted on the base plate 68. Since it is the general practice at the present time to tune radio circuits by means of variable condensers, I have shown condenser plates 69 fixed on shaft 64 and condenser plates 70 which are held stationary in any suitable way. Sometimes all the tuning elements are mounted on a single shaft, but in certain designs of receivers the gangs of tuning condensers are mounted on separate shafts coupled for simultaneous operation. Nor is it necessary that the tuning elements be mounted on shaft 64, for they may obviously be supported on one or more separate shafts operatively connected to shaft 64. The particular form, arrangement and mounting of the tuning elements are not important in connection with this invention, and it will therefore be understood that the shaft 64 represents broadly a movable member for adjusting the tuning elements of a radio receiver. The front end of shaft 64 carries a suitable indicator 71, which is here shown as a semi-circular plate carrying the usual notations to identify the different broadcasting stations. The indicating marks on disk 71 are visible through an opening 72 in front panel 65.

Since tuning condensers are usually so constructed that a half-revolution of the movable plates covers the whole tuning range from maximum to minimum capacity, I have provided means for automatically reversing the direction of shaft 64 at the end of each half revolution. A gear 73 fixed on shaft 64 meshes with a pinion 74 mounted on a spindle 75 which is rotatably supported in bearings 76 and 77. The rear bearing 76 is part of the upright bracket 67, and bearing 77 may be attached to the front panel 65. A second pinion 78 on spindle 75 meshes with a rack bar 79 projecting from a reciprocable frame 80. The rack bar 79 has a slot 81 for receiving a grooved roller 82 mounted on a pin 83, and the frame 80 is supported between a pair of grooved

rollers 84 mounted on pins 85. The pins 83 and 85 may conveniently be secured to the front panel of the receiver cabinet. The reciprocable frame 80 comprises an upper rack bar 86 and a lower rack bar 87. The rack bar 79 and frame 80 may be cast, stamped or molded as a single piece either from metal or strong insulating material. An electric motor 88 has a driving shaft 89 provided with a worm or spiral pinion 90 arranged in permanent mesh with a worm gear 91 fixed on a rotary shaft 92. A bracket 93 projecting from the housing of motor 88 supports the shaft 92, which carries a half gear 94 arranged to operate between the rack bars 86 and 87, as best shown in Fig. 9.

Assuming that the half gear 94 always rotates in a clockwise direction (as viewed in Fig. 9), it is evident that when the gear teeth engage the lower rack bar 87, the frame 80 is moved to the left a predetermined amount. During the engagement of half gear 94 with the upper rack bar 86, the frame 80 is shifted an equal amount toward the right. The rack frame 80 and half-gear 94 are so constructed that for a half revolution of shaft 92 the frame is moved in one direction, and during the other half revolution of the shaft the frame is moved in the reverse direction. These reciprocations of frame 80 are communicated to the tuning shaft 64 through gear connections 79—78 and 74—73. The transmission ratios of these connections are so calculated that during each movement of frame 80 the tuning shaft 64 is moved through full tuning range, which means from one end of dial 71 to the other. The reason why the indicator disk 71 is cut away at 95, as shown in Fig. 12 is to avoid such parts as would otherwise be in its path of movement. The speed reduction between the motor shaft 89 and the tuning shaft 64 is sufficient to cause movement of the latter at the requisite low speed, which may approximate the speed of hand tuning.

I prefer to include provisions for tuning the shaft 64 by hand without going through the motor driving connections. For this purpose the 45 spindle 75 is mounted for axial movement in addition to its rotary movement. A spring arm 96 mounted on bracket 67 engages the rear end of spindle 75 and normally holds the same in forward position, as shown in Fig. 8. The front end 50 of spindle 75 carries a knob 97 or other suitable finger piece for conveniently manipulating the spindle by hand. A grooved collar 98 fixed on spindle 75 engages a pair of rollers 99 carried by one end of a lever 100, which is pivoted on a pin 55 101 supported on a suitable bracket 102. This bracket may conveniently be attached to the front panel 65 by screws 103 or otherwise (see Fig. 9). The other end of lever 100 terminates in a yoke 104 having rollers arranged to engage in the annular groove 105 of a clutch ring 106, which is slidably and loosely mounted on shaft 92. A clutch member 107 fixed on shaft 92 is adapted to engage the slidable clutch ring 106 for coupling the latter to the shaft. The clutch ring 106 is connected to the half-gear 94, which therefore partakes of the slidable and rotary movements of the clutch ring. The parts 94 and 106 are in effect a single member mounted loosely on shaft 92 and adapted to be connected to the shaft 70 when clutch ring 106 is shifted into locking engagement with clutch member 107, as shown in Fig. 10. The teeth of the half gear 94 are sufficiently wide to maintain engagement with rack frame 80 in either position of clutch ring 106.

- In the normal position of spindle 75 as determined by the spring arm 96, the clutch members 106 and 107 are held in locking engagement, so that the tuning shaft 64 is operatively connected to the driving shaft 89 of motor 88. When a person wants to tune the receiver by hand independently of the motor, the knob 97 is pushed in as far as it will go. The inward movement of spindle 75 is limited either by the pinion 74 striking the front face of bearing 76, or by the rear edge 108 of knob 97 striking the front panel 65. The spring arm 96 is of such flexibility that it does not offer undue resistance to the inward movement of knob 97. It is clear from Fig. 10 that, when the spindle 75 is pushed in, the right end of lever 100 is rocked forwardly, so that the clutch ring 106 is moved out of engagement with clutch member 107 and the half gear 94 is disconnected from the motor shaft. When the hand knob 97 is rotated while being held pushed in, the rotation of spindle 75 is communicated to shaft 64 through gear connection 74-73. At the same time the rack frame 80 and half gear 94 are reciprocated, but these movements are idle and offer no appreciable resistance to the rotation of spindle 75.
- It is necessary to connect the half gear 94 and rack frame 80 permanently to spindle 75 in order to maintain the same relation between those parts. For example, looking at Fig. 9, we see that the half gear 94 and rack bar 87 are in a midway position, and consequently the tuning shaft 64 must be in a midway position with respect to the station dial 71. This midway position of shaft 64 is indicated by the midway position 69' of the tuning elements 69. When the half gear 94 breaks connection with the lower rack bar 87 and is about to engage the upper rack bar 86, the tuning shaft 64 is at one end of its range of movement and is ready to reverse its direction of rotation. This operative relation between shaft 64 and half gear 94 is maintained permanently, irrespective of whether the spindle 75 is turned by means of the hand knob 97 or by the electric motor 88. As soon as the operator releases the knob 97, the spring arm 96 throws the spindle forward to normal position and locks the clutch members 106-107. The pinions 74 and 78 on spindle 75 are sufficiently wide to remain in mesh with their associated gear members in either position of the spindle.
- An upright frame or panel 109 is secured at its lower end to a plate 110, which may be an integral part of bracket 67. An opening 112 in panel 109 makes room for shaft 64. The upper end of panel 109 carries a set of contact pieces 113, which may be small plates of brass or other good conducting metal forced into peripheral slots 114, so that no separate fastening means is necessary. The supporting panel 109 is preferably of insulating material, like bakelite, so that no separate insulation is needed for the individual contacts 113. The radial arrangement of these contacts is such that each one represents a selected station. A lug or extension 115 on each contact 113 provides means for easily attaching the necessary conductors. In the present instance there are ten contacts 113 to represent the ten stations marked A-K on the indicator of control box 10. The tuning shaft 64 carries an insulating hub or collar 116 on which a switch arm 117 is mounted. A set-screw 118 (see Fig. 10a) locks the collar 116 to shaft 64. A ring 119 of good conducting metal is rigidly mounted on the insulating hub 116 and is in permanent contact with a brush or switch arm 120, which is supported at one end on an insulated bracket or lug 121 projecting from panel 109. The rotary switch arm 117 is connected to ring 119 by screws 122, so that these two parts are in permanent electric contact. The collector ring 119 may also be made as an integral hub of switch arm 117. The free end of arm 117 preferably terminates in a lateral offset or nose 123 for engaging the contact pieces 113 with pressure. If desired, these contact pieces may be mounted like the contact pieces 27 in Fig. 6, so that the radial switch arm 117 snaps into firm engagement with contacts 113. The arm 117 is preferably made of spring material to press the nose or lateral offset 123 against the face of panel 109 and contacts 113.
- A bracket 124 attached to the rear side of panel 109 carries a solenoid coil 125 which has a soft iron core 126. An arm or lever 127 is pivoted on a pin 128 projecting rearwardly from panel 109. If the lever 127 is non-magnetic, it is provided with an armature piece 129 arranged to be attracted by the electromagnet 125-126 when the same is energized. A bracket 130 on panel 109 carries a contact 131, which may simply be the head of a bolt 132. Nuts 133 on the lower end of bolt 132 may be used as a binding post for a conductor. An insulated contact 134 mounted on lever 127 is normally held against contact 131 by a contracting coil spring 135. The lower end of this spring is connected to a pin 136 extending rearwardly from panel 109, and the upper end of the spring is attached at 137 to the pivoted lever 127. When the coil 125 is energized, the left end of lever 127 is raised to separate contact 134 from contact 131. When the coil is de-energized, the spring 135 instantly closes the switch contacts 134 and 131. These contacts constitute a switch in the circuit of motor 88, as will presently be explained.
- Fig. 13 is a diagram showing the circuit connections between the control box 10 and the radio receiver. To facilitate the tracing of circuits I have differentiated the contacts 27 of the control box and the contacts 113 of the radio receiver by the suffix letters A-K, which are supposed to represent ten different stations. The contacts 27A-27K are connected to contacts 113A-113K by conductors 138A-138K, respectively. A plug 139 adapted to be inserted in a house-lighting socket is connected to a pair of service leads 140 and 141. The switch arm 51 of the control box is connected to the switch arm 117 of the radio receiver by a conductor 142, which is connected to main 141. The other main 140 is connected by a conductor 143 to terminal 144 of motor 88, and a conductor 145 connects main 140 to one side of the solenoid coil 125. If desired or found necessary, resistances 146 and 146' are inserted in the circuits of coil 125 and motor 88 to cut down the voltage. The other side of coil 125 is connected by a conductor 147 to the rotary selector arm 43 of the control box. The signal lamp 57 is included in conductor 147 and may be shunted by a resistance 148 so as not to interfere with the operation of the tuning apparatus if the lamp should accidentally burn out. The second motor terminal 149 is connected by conductor 150 to contact 134 which is mounted on the pivoted lever 127. The associated contact 131 is connected by a conductor 151 to the contact strip 36 of the control box 10. The contact arm 52 in the control box is connected by a conductor 152 to the electric driving unit of a suitable loudspeaker 153, which is in-

dicated merely in a diagrammatic way at the bottom of Fig. 13. The other side of the loudspeaker circuit is connected by a conductor 154 to contact strip 33. When the switch members 5 33 and 52 are in engagement, the operating circuit of loudspeaker 153 is closed. This condition obtains, as previously explained, when the push button 20 is in normal raised position. When the button is pushed down, the switch 33-52 is 10 opened and the loudspeaker is silent.

Let us suppose that the pointer 18 of control box 10 has been turned to station E, as shown in Fig. 1. The switch arms 43, 51 and 52 will then be in the position shown in Fig. 13. Nothing happens by the mere rotation of knob 16 to adjust the pointer 18, because the circuit of motor 88 remains open and the tuning shaft 64 is not operated. When the button 20 is pushed down after station E has been selected by pointer 18, 15 the switch arm 43 engages contact 27E and switch arm 51 engages contact strip 36, whereby the motor circuit is closed as follows: Starting with service main 140, conductor 143, through the windings of motor 88, conductor 150, across the closed contacts 134-131, conductor 151, across the closed contacts 36-51, conductor 142 and return lead 141. The energized motor now operates the tuning shaft 64 through the transmission connections previously described in detail. 20 The shaft 64 is rotated in one direction or the other until the arm 117 fixed on the shaft engages contact 113E. When this happens, the circuit of coil 125 is closed as follows: Starting with service main 140, conductor 145, coil 125, 25 conductor 147, switch arm 43, conductor 138E, contact 113E, switch arm 117, conductor 142 and return lead 141. When coil 125 is energized, it pulls the adjacent end of lever 121 down and abruptly pulls contact 134 away from contact 30 131, so that the motor circuit is interrupted and shaft 64 remains in tuning position. If necessary or desirable, a brake may be used to stop rotation of the motor shaft instantly when switch 35 131-134 is opened. The signal lamp 57 lights up when coil 125 is energized to inform the operator that the shaft 64 is in tuning position for 40 the selected station. As soon as the operator receives the signal from lamp 57, he releases the push button 20 which opens the motor switch 45 36-51 and also breaks the circuit of coil 125 by raising the switch arm 43 away from contact 27E. The electric motor 88 and switch-operating coil 125 do not therefore consume any current after 50 the desired station has been tuned in. Since 55 the loudspeaker switch 33-52 remains open during the operation of shaft 64 by motor 88, the loudspeaker is silent during the tuning operation. As soon as the button 20 is released, the switch 60 33-52 is closed and the loudspeaker is in operative condition to reproduce the broadcast reception. In a simpler form of my invention, the signal lamp 57 and the loudspeaker switch 33-52 may be omitted from the control box 10.

The circuits described in the preceding paragraph for station E are the same for any one of the other stations marked on the indicator of control box 10, except that the circuit of coil 125 is closed only when the arms 43 and 117 indicate corresponding contacts. For example, when 65 pointer 18 is moved to select station B and button 20 is pushed down, the connected switch arm 43 engages contact 27B and the shaft 64 is stopped in tuning position for station B as soon as the rotary switch arm 117 engages contact 113B. 70 75 This explanation also applies to each of the other

stations. A person may sometimes want to get a station not included in the ten stations marked on control box 10. In that case it is only necessary to move pointer 18 into position 18' (see Fig. 1) opposite the notation "Any Station". When the pointer is in position 18', the switch arms 43, 51 and 52 are in position 43', 51' and 52', respectively (see Fig. 13). In other words, the switch arm 43 is out of operative relation to contacts 27, but the other two switch arms 51 and 52 are still 10 in alignment with the associated contact strips 36 and 33. When the button 20 is pushed down after the pointer has been moved to position 18', the motor switch 36-51 is closed and the tuning shaft 64 is operated until the desired station is 15 received, whereupon the button is released. During this tuning operation it is necessary to keep the loudspeaker circuit closed, so that a person can hear each station as it crosses the tuning point during the rotation of shaft 64. This is 20 accomplished by providing the contact strip 33 with a return extension 33' at the bottom, as shown in Fig. 5. When the button 20 is pushed down, the switch arm 52 engages the return extension 33' so that the loudspeaker switch 33-52 25 remains closed. The tuning shaft 64 operates at sufficiently low speed to enable a person to hear the kind of programs sent out by the different stations.

In the modification of Figs. 14-17, the knob 16 and push button 20 of Fig. 2 are replaced by a single knob 155, which has both a rotary movement for selecting the desired station and an axial movement for closing the necessary circuits. All those parts that are common to the two constructions shown on sheets 1 and 5 are indicated by the same reference numerals to avoid needless repetition of description. The knob 155 is preferably an integral projection of a molded insulating piece 156, which is extended to form a thin semi-circular disk 157. I have assumed that the control box 10 of Fig. 14 has five contacts 27 for tuning in five selected stations. Consequently, the disk 157 is provided with five indicating marks 158 which represent stations A-E. The top of box 10 has a sight opening 159 through which the station indicia on disk 157 are visible. In Fig. 14, for instance, the knob 155 is turned for tuning in station C. The switch arm 43 is attached to a radial extension or lug 160 below the indicator disk 157. The other two switch arms 51 and 52 50 are secured to lateral extensions 161 and 162 of a hollow hub or sleeve 163 projecting from part 156. The lower end of hub 163 may engage in an annular recess 164 for guiding the movements of knob 155 and all parts carried thereby. An expanding coil spring 165 arranged within sleeve 163 normally holds the knob 155 and its connected members in raised position, exactly as described in connection with the push button 20 in Fig. 2. A circular depending flange 166 in the top of box 60 10 extends into an annular groove 167 at the base of knob 155 and acts as an upper bearing for the latter. At the same time, the engagement of flange 166 in groove 167 limits the upward movement of knob 155 under the action of spring 165. 65 The projecting end of knob 155 is so shaped that it is easily grasped by the fingers for rotary movement, and it may have a central depression 168 to facilitate the operation of the knob as a push button. The circuit diagram of Fig. 13 applies fully 70 to the control box of Figs. 14-17. To bring in a station not represented by the notations on disk 157, the knob 155 is turned until the indicator line 169 is opposite the point 170 of window 159. When the knob 155 is then pushed down, the same 75

operation takes place that was described in connection with push button 20 when the pointer 18 is in position 18'.

Figs. 18-20 illustrate a modification in which 5 the stationary contacts 143 and the rotary switch arm 117 of the radio receiver are replaced by a set of disks 171 fixed on the tuning shaft 64 and carrying each a contact 172 arranged to connect a pair of switch arms 173-174. All parts 10 common to the diagrams of Figs. 13 and 18 are indicated by the small reference numerals to avoid needless repetition of description. While Fig. 13 shows ten different stations which are 15 automatically tuned in, Fig. 18 has been purposely simplified by using only five stations A-E. For distinction the tuning disks 171 are differentiated by the suffix letters A-E, and the same applies to the different pairs of switch arms 173-174. The individual contacts 27A-27E are 20 connected to switch arms 174A-174E by conductors 175A-175E, respectively. One side of coil 125 is connected to switch arm 51 by a conductor 176 which is connected to service lead 141. The other side of coil 125 is connected by a conductor 177 to switch arms 173A-173E, which are 25 connected in parallel to that conductor. The signal lamp 57 is connected in series with coil 125, but it may be omitted if desired. The motor terminal 144 is connected to switch arm 43 by a conductor 178. The tuning disks 171 in Fig. 18 are 30 shown in face view side by side, but in actual practice they are mounted on shaft 94 as close together as mechanical conditions permit. A suitable mounting for disks 171 is illustrated in 35 Figs. 19 and 20. The switch arms 173 and 174 may be mounted on a common bar 179 secured to a bracket 180.

Still referring to Fig. 18, the contacts 172 on 40 disks 171 are arranged in such angular relationship that each contact connects the associated switch arms 173-174 when the station represented by that contact is in tune. Let us suppose that 45 we wish to bring in station C. If the control box of Fig. 1 is used, the pointer 18 is turned to the indicating line C; and if the control box of Fig. 14 is used, the knob 155 is turned until the C mark shows centrally through the window 159. When 50 the tuning button 20 or knob 155 is pushed down, the circuit of motor 88 in Fig. 18 is closed as follows: Starting with service lead 140, conductor 178, through the windings of motor 88, conductor 150, across the closed switch contacts 134-131, conductor 151, through the closed switch 36-51, conductor 176 and the return lead 141. The tuning 55 shaft 64 and disks 171 are rotated until the contact 172 of disk 171C connects the associated switch arms 173C-174C. The circuit of coil 125 is now closed as follows: Main 140, conductor 178, switch arm 43, contact 27C, conductor 175C, across the closed switch 174C-173C, conductor 177, lamp 57, coil 125, conductor 176 and return 60 lead 141. The energizing of coil 125 abruptly opens the switch 131-134, so that the motor circuit is interrupted and the shaft 64 stops in tuning 65 position for the selected station C. The circuits for any one of the other stations are traced in a similar manner, as will be understood without the need of further detailed description.

Figs. 21 and 22 show a simplification of the 70 control box illustrated on the first sheet of the drawings. Here the sleeve 37 of knob 16 carries a contact ring or collar 181 which may be screwed on or held in place by a set-screw 182. A hole 183 in the side of box 10 permits the insertion of a 75 screw-driver for tightening the screw 182. The

switch arm 43 is attached to the underside of collar 181 by screws 184, or otherwise. The free end of arm 43 wipes over the top of bridge piece 25 whenever it comes into alignment with one of them. An insulating washer 185 on sleeve 37 engages the lower edge of a depending flange 186 on the top of box 10 to prevent axial movement of knob 16 and at the same time insulate the contact ring 181 from the sheet metal cover of 10 the box. The lower portion of push button 20 passes through a hollow boss 187 on base 12 and rests on the free end of a spring arm 188, which is attached to the base by screws 189 or otherwise. One of these screws may be used as a binding post for a conductor. When the button 20 is pushed down, the free end of switch arm 188 engages a fixed contact 190 suitably mounted on base 12. An insulating post 191 projecting from base 12 carries a spring arm 192 arranged in 15 permanent contact with the metal ring 181 of switch arm 43. It will not be necessary to show the diagram of circuit connections for the control box of Figs. 21 and 22, because substitution of this box in Figs. 13 and 18 is so obvious as to 20 require no detailed description. The switch 188-190 of Figs. 21 and 22 takes the place of switch 36-51 in Figs. 13 and 18. The lamp 57 and loud-speaker switch 33-52 of Figs. 13 and 18 have 25 been omitted in the control box of Figs. 21 and 30 22, but they may be added if desired.

Still another form of control box embodying certain features of my invention is shown in Figs. 23-26, where the selector arm 43 is operated by means of a button 193, which is attached 35 to the arm through a stem 194. The switch arm 43 is rotatably mounted on a pin 195 which is screwed into a central post 196 of base plate 12. The stem 194 of button 193 extends through a semi-circular slot 197 in the top of box 10, and 40 a pointer 198 on button 193 moves over a scale 199 which consists of radial lines representing nine different stations marked A-J. A second switch arm 200 in the control box is connected with switch arm 43 by an insulating piece 201, 45 so that the two arms move down and up as a unit. These two arms are connected to a pair of insulated metal rings or collars 202 and 203 respectively, which are rotatably mounted on pin 195 and insulated therefrom by a bushing 204 of 50 bakelite, hard rubber and the like. An insulating post 205 projecting from base 12 carries a pair of spring arms 206 and 207 which are in permanent contact with the insulated rings 202 and 203 respectively. Below the free end of 55 switch arm 200 is a contact strip 208 mounted on a lateral extension or shelf 209 of bridge 25. The bushing 204 has a key 210 projecting into aligned axial slots 211 in contact rings 202 and 203, whereby the switch arms 43 and 200 are 60 locked together for simultaneous rotation. If the insulating lug 201 is secured to both switch arms 43 and 200, the locking key 210 is not necessary. In Fig. 24, the lug 201 is attached to the upper 65 switch arm 43 by a screw 212 and its lower end need only touch the switch arm 200 if locking key 210 is used. Any other practical arrangement may be employed for mounting the switch arms 43 and 200 so that they operate as a unit both for rotation and for vertical movement. 70

Still referring to Figs. 23-25, when a person wants to tune in a particular station, he moves the button 193 until the pointer 198 is opposite the indicating mark of the station wanted. The button 193 is then pushed down, whereupon the 75

switch arm 43 engages the proper contact 27 and at the same time the lower switch arm 200 engages the contact strip 208 to close the circuit of motor 88. It is not believed necessary to show a separate circuit diagram for the control box of Figs. 23-25, because the substitution of this box in Figs. 13 and 18 is evident to those skilled in the art. I need only say that the motor switch 200-208 of Fig. 24 takes the place of the motor switch 36-51 of Figs. 13 and 18. The switch arms 43 and 200 are made of spring metal, so that they are pushed down without undue resistance. This downward movement need be but a small fraction of an inch. The normal tension of spring arms 43 and 200 holds them in open position and restores them to normal raised position when the button 193 is released.

Attention is called to the fact that no high-voltage wires are in the electric cable that connects the control box with the radio receiver. The small motor 88 and coil 125 operate on such low voltage that no arcing occurs at the switch contacts in the control box. The latter can be made small and compact, because it contains no solenoids or other parts that take up much space. The control mechanism in the receiver cabinet is comparatively simple. In the basic aspect of my invention, any practical means may be employed for reversing the tuning shaft at each end of the dial. For example, a reversing switch for the motor may be used, but personally I prefer to have the motor shaft run always in the same direction and to reverse the transmission connections.

Although I have shown and described certain specific constructions, my invention is not limited to the details set forth. Changes and modifications will probably occur to others without departing from the scope of the invention as defined in the appended claims. I might add that the drawings have not been made to accurate scale and are not therefore to be regarded as shop drawings in which every minute part has been carefully calculated. I have purposely exaggerated some of the parts to make the drawings as clear as possible.

I claim as my invention:

1. In radio tuning apparatus, a remote control box having a series of electric contacts representing each a selected station, a rotary switch arm normally out of engagement with said contacts and movable axially into engagement with a selected contact, a normally open motor switch in said box, a manually operable member for closing said switch arm against any one of said contacts and at the same time closing said motor switch, and spring means for automatically restoring said switch arm and motor switch to normal position upon the manual release of said member, in combination with a radio receiver having adjustable tuning means, an electric motor for operating said tuning means, said normally open switch being connected in the circuit of said motor, and control mechanism operatively connected with said contacts to stop said motor when said tuning means has tuned in the station represented by the particular contact which said switch arm engages when the motor switch is closed.

2. In radio tuning apparatus, a remote control box having a series of electric contacts representing each a selected station, a rotary switch arm normally out of engagement with said contacts and movable axially into engagement with a selected contact, a normally open motor switch

in said box, a push button on top of said box for closing said switch and moving said switch arm axially into engagement with the selected contact, and means whereby said motor switch and station-selecting switch are instantly opened by the manual release of said push button, in combination with a radio receiver having adjustable tuning means, an electric motor for operating said tuning means, said normally open switch being connected in the circuit of said motor, and control mechanism operatively connected with said contacts to stop said motor when said tuning means has tuned in the station represented by the particular contact which said switch arm engages when the motor switch is closed.

3. In radio tuning apparatus, a remote control box having an adjustable finger piece on top, means whereby said finger piece is compressible in any adjusted position, said finger piece being normally held in raised position, a series of switch contacts in said box representing selected stations, a switch member connected to said finger piece and movable therewith to engage any one of said contacts when the finger piece is pushed in, and means whereby the manual release of said finger piece instantly disengages said switch member from the selected contact, in combination with a radio receiver having adjustable tuning means, an electric motor for operating said tuning means, and electric control mechanism operatively connected with said station-selecting contacts and adapted to stop said motor when said tuning means has tuned in the station represented by the particular contact which said switch member engages, said mechanism including a plurality of separately operable circuits connected each to one of said contacts and an electromagnetic switch automatically energized upon the closing of any one of said separate circuits to open the motor circuit, each of said separate circuits being automatically closed when the station represented by the selected contact is in tune, the manual release of said finger piece automatically opening the closed circuit.

4. In radio tuning apparatus, a remote control box containing a normally open motor switch and a normally closed loudspeaker switch, manually operable means for simultaneously closing said motor switch and opening said loudspeaker switch, and connections whereby the manual release of said switch-operating means instantly restores said switches to normal condition, in combination with a radio receiver having adjustable tuning means and a loudspeaker, an electric motor for operating said tuning means, said motor switch and said loudspeaker switch being connected respectively in the circuit of said motor and in the circuit of said loudspeaker, and means whereby the operation of said manual means automatically causes said motor to tune in a desired station by adjusting said tuning means, the loudspeaker circuit remaining open until said manual means is released, whereupon the loudspeaker switch is automatically closed and the motor switch is opened.

5. In radio tuning apparatus, a remote control box having a series of electric contacts representing each a selected station, a rotary switch arm movable into engagement with a selected contact, a normally open motor switch in said box, manually operable means for closing said switch, a normally closed loudspeaker switch in said box, connections whereby said loudspeaker switch is opened when said motor switch is closed,

- and means whereby the manual release of said switch-operating means instantly restores said motor switch and loudspeaker switch to normal condition, in combination with a radio receiver having adjustable tuning means and a loudspeaker, an electric motor for operating said tuning means, said motor switch and said loudspeaker switch being connected respectively in the circuit of said motor and in the circuit of 5 said loudspeaker, electric control mechanism operatively connected with said contacts to stop said motor when said tuning means has tuned in the station represented by the particular contact which said switch arm engages when the 10 motor switch is closed, the loudspeaker circuit remaining open until said manual means is released, whereupon the loudspeaker switch is automatically closed and the motor switch is opened.
- 15 6. In radio tuning apparatus, a remote control box having a pivotally mounted finger piece, an indicating device movable with said finger piece, a fixed indicating device on top of said box, one of said indicating devices bearing marks to designate certain selected stations, a series of switch contacts in said box representing said selected stations, a switch member operated by said finger piece to engage any one of said contacts, and means whereby the manual release of said finger piece instantly disengages said switch member from the selected contact, in combination with a radio receiver having a tuning shaft rotatable in opposite directions through a predetermined arc, an electric motor for operating said shaft 20 in either direction through its arc of travel, a plurality of separately operable electric circuits connected each to one of said station-selecting contacts, connections whereby any one of said separate circuits is closed when said shaft is in tuning position for the station represented by the engaged contact, said connections including contact means synchronously movable with said shaft, a normally closed switch in the motor circuit, electromagnetic means automatically energized when said shaft is in selected tuning position for opening said motor switch, and means whereby said motor switch is automatically closed when said finger piece is released.
- 25 7. In radio tuning apparatus, a remote control box having a series of electric contacts representing each a selected station, a rotary switch arm associated with said contacts and normally held spaced therefrom, whereby said arm may be rotated without engaging said contacts, a normally open motor switch in said box, manually operable means for moving said arm into engagement with a selected contact and at the same time closing said motor switch, and means whereby the manual release of said switch-operating means instantly opens said switch arm and motor switch, in combination with a radio receiver having adjustable tuning means, an electric motor for operating said tuning means, said normally open switch being connected in the circuit of said motor, and electric control mechanism operatively connected with said contacts to stop said motor when said tuning means has tuned in the station represented by the particular contact which said switch arm engages when 30 said motor switch is closed, said control mechanism including a second switch in the motor circuit in series with said first motor switch, said second motor switch being normally closed and being automatically opened when said tuning means is in preselected tuning position, the re- 35 lease of said manually operable station-selecting means automatically opening all circuits of said control mechanism.
- 35 8. In radio tuning apparatus, a remote control box having a series of electric contacts representing each a selected station, a rotary switch arm associated with said contacts and normally held spaced therefrom, whereby said arm may be rotated without engaging said contacts, a normally open motor switch in said box, a push button on top of said box for moving said arm into engagement with a selected contact and at the same time closing said motor switch, and means whereby the manual release of said push button instantly disengages said switch arm from the selected contact and opens the motor switch, in combination with a radio receiver having adjustable tuning means, an electric motor for operating said tuning means, said normally open switch being connected in the circuit of said motor, and electric control mechanism operatively connected with said contacts to stop said motor when said tuning means has tuned in the station represented by the particular contact which said switch arm engages when the push button is operated, said electric control mechanism including circuits which are automatically opened upon release of said push-button.
- 40 9. In radio tuning apparatus, a remote control box having a pivotally mounted finger piece on top, means whereby said finger piece is depressible, said finger piece being normally held in raised position, a series of switch contacts in said box representing selected stations, a switch member connected to said finger piece and movable therewith to engage any one of said contacts when the finger piece is depressed, a normally open motor switch in said box, means for closing said motor switch when said finger piece is pushed down, and means whereby the manual release of said finger piece instantly disengages said switch member from the selected contact and opens the motor switch, in combination with a radio receiver having adjustable tuning means, an electric motor for operating said tuning means, said normally open switch being connected in the circuit of said motor, and control mechanism operatively connected with said contacts to stop said motor when said tuning means has tuned in the station represented by the particular contact which said switch arm engages when the motor switch is closed.
- 45 10. A radio receiver having variable tuning means, a rotary shaft for operating said tuning means, said shaft being rotatable in either direction through a predetermined arc to cover the whole broadcasting range, an electric motor normally connected to said shaft for operating the same, means for controlling the operation of said motor to tune in any desired station, a rotary hand knob permanently connected to said tuning shaft for manually operating said shaft independently of said motor, and means controlled by said knob for uncoupling said motor from said shaft when the latter is turned by hand, said disconnecting means including a manually adjustable transmission member.
- 50 11. A radio receiver having variable tuning means, a rotary shaft for operating said tuning means, said shaft being rotatable in either direction through a predetermined arc to cover the whole broadcasting range, an electric motor normally connected to said shaft for operating the same, means for controlling the operation of said motor to tune in any desired station, a hand-op-

erable spindle connected to said shaft for actuating the same independently of said motor, a finger piece permanently connected to said spindle for manual operation thereof, and means controlled by said spindle for disconnecting the motor from the tuning shaft when the latter is operated by the spindle, said means including a manually adjustable transmission member.

12. A radio receiver having variable tuning means, a rotary shaft for operating said tuning means, said shaft being rotatable in either direction through a predetermined arc to cover the whole broadcasting range, an electric motor connected to said shaft for operating the same, means for controlling the operation of said motor to tune in any desired station, a hand-operable rotary spindle connected to said shaft for actuating the same independently of said motor, a finger piece permanently connected to said spindle for manual operation thereof, said spindle being also mounted for axial movement, and a clutch controlled by the axial movements of said spindle for disconnecting the motor from the tuning shaft when the latter is operated by the spindle.

13. The combination of a rotary shaft, a set of circularly arranged stationary contacts representing each a selected position of the shaft, a pivoted switch arm movable with said shaft and arranged to engage said contacts with which said arm moves into and out of separable frictional engagement, whereby said contacts do not obstruct the rotary movement of said arm through a predetermined arc in either direction, a single electric motor for operating said shaft in alternately opposite directions, means for automatically reversing the rotation of said shaft at each end of its arc of travel, and selectively operable means for automatically opening the motor circuit when said arm engages a predetermined contact, whereby said shaft stops in selected position.

14. The combination of a rotary shaft, a single electric motor for operating said shaft in opposite directions through a predetermined arc, a set of circularly arranged contacts representing each a selected position of said shaft, a pivoted switch arm movable with said shaft and arranged to engage said contacts, means for automatically reversing the rotation of said shaft at each end of its arc of travel, a remote control device having a rotary switch arm, a set of contacts arranged to be engaged by said last-mentioned switch arm to select any position of said shaft, and means whereby the motor circuit is automatically opened to stop said shaft when said switch arms engage corresponding contacts, said last-mentioned means being operative irrespective of the angular position from which said shaft starts to rotate.

15. The combination of a rotary shaft, a set of circularly arranged contacts representing each a selected position of said shaft, a pivoted switch arm movable with said shaft and arranged to engage said contacts, a single electric motor for operating said shaft in opposite directions through a predetermined arc, means for automatically reversing the rotation of said shaft at each end of its arc of travel, a remote control device having a movable finger piece to select any one of said stations, connections controlled by said finger piece for automatically opening the motor circuit when said arm engages a predetermined contact, whereby said shaft stops in selected position, and means whereby said circuit-

opening connections are operative irrespective of the angular position from which said shaft starts to rotate.

16. The combination of a shaft rotatable in opposite directions through a predetermined arc, a single electric motor for operating said shaft in both directions, a set of electric contacts representing each a selected position of said shaft, a switch arm movable with said shaft to engage said contacts, means for automatically reversing the movement of said shaft and switch arm at each end of their path of travel, a remote control device having a set of contacts electrically connected individually to said first-mentioned contacts, a manually operable switch arm carried by said device and movable into engagement with any one of the second set of contacts for selecting a position in which said shaft shall stop, and means whereby the motor circuit is automatically interrupted when the two switch arms engage a pair of connected contacts, said circuit-interrupting means being operative irrespective of the angular position from which said shaft starts to rotate.

17. The combination of a rotary shaft, a set of electric contacts representing each a selected position of said shaft, a switch arm rotatable with said shaft and arranged to engage said contacts, a single electric motor connected to said shaft for operating the same in alternately opposite directions through a predetermined arc, means whereby the rotation of said shaft is automatically reversed at each end of its arc of travel, a normally closed switch in the motor circuit, an electromagnet adapted when energized to open the motor switch, said electromagnet comprising a coil, a remote control device having a set of contacts electrically connected individually to said first-mentioned contacts, and manually operable means carried by said control device for selecting any one of the second set of contacts to close the circuit of said coil and thereby open the motor circuit when said switch arm engages the particular contact which corresponds to the selected contact of said control device.

18. The combination of a rotary shaft, a single electric motor for operating said shaft in opposite directions through a predetermined arc, switch mechanism associated with said shaft to control its operation, said mechanism including a set of stationary contacts and also contact means movable with said shaft to engage said contacts individually, means for automatically reversing the rotation of said shaft at each end of its arc of travel, a remote control device having a set of selector contacts electrically connected individually to said first-mentioned contacts, a manually operable switch arm carried by said device and movable into engagement with any one of said selector contacts for selecting a position in which said shaft shall stop, and connections whereby the motor circuit is automatically interrupted by said movable contact means engaging the particular tuning contact which is electrically connected to the selector contact engaged by said switch arm in the control box, said motor-stopping connections being operative irrespective of the angular position from which said shaft starts to rotate.

19. In radio tuning apparatus, a remote control box containing a loudspeaker switch, station-selecting means in said box, and a spring-pressed push button on said box for operating said switch and station-selecting means, the manual release of said push button instantly restoring the same

- to normal position, in combination with a radio receiver having adjustable tuning means and a loudspeaker, mechanism for operating said tuning means, operative connections between said station-selecting means and said mechanism whereby the operation of said means by said push button automatically causes said mechanism to adjust said tuning means for the selected station, means for connecting said switch in the circuit of said loudspeaker, and means whereby the operation of said push button renders the loudspeaker inoperative, the release of said push button automatically operating said switch to render the loudspeaker operative.
- 15 20. In radio tuning apparatus, a radio receiver having adjustable tuning means and a loudspeaker, means for operating said tuning means, in combination with a remote control box containing a normally closed switch connected in the circuit of said loudspeaker, manually controllable station-selecting mechanism carried by said box and operatively connected with said operating means to adjust said tuning means for a selected station, said mechanism including an adjustable finger piece, means for automatically opening said switch when said mechanism is in operative position to render said loudspeaker inoperative during the tuning operation, and means whereby the operator's release of said finger piece instantly restores said switch to normal condition and renders said loudspeaker operative.
- 25 21. In radio tuning apparatus, a remote control box having a finger piece mounted for independent rotary and axial movements, a series of normally open switch contacts in said box representing certain selected stations, means whereby the rotary adjustment of said finger piece selects one of said switch contacts for operation, means whereby the axial movement of said finger piece 30 closes the selected contact, and means whereby the operator's release of said finger piece instantly opens said closed contact, in combination with a radio receiver having an adjustable tuning shaft, an electric motor for operating said shaft, a plurality of separately operable electric circuits connected each to one of said station-selecting contacts, connections whereby any one of said separate circuits is closed when said shaft is in tuning position for the station represented by the engaged contact, said connections including contact means synchronously movable with said shaft, a normally closed switch in the motor circuit, electromagnetic means automatically energized when said shaft is in selected tuning position for opening said motor switch, and means whereby said motor switch is automatically closed when said finger piece is released.
- 35 40 45 50 55 22. In radio tuning apparatus, a remote control box containing a series of circularly arranged contacts which represent each a certain station, a rotary switch arm normally in a position where it can not engage said contacts, means whereby said arm is movable into engagement with any one of said contacts after the arm has been rotatably adjusted to select a certain station, said means including a movable finger piece, and means whereby the manual release of said finger piece disengages said switch arm from the selected contact, in combination with a radio receiver having an adjustable tuning shaft, an electric motor for operating said shaft, a plurality of separately operable electric circuits connected each to one of said station-selecting contacts, connections whereby any one of said separate circuits is closed when said shaft is in tuning position for the station

represented by the engaged contact, said connections including contact means synchronously movable with said shaft, a normally closed switch in the motor circuit, electromagnetic means automatically energized when said shaft is in selected tuning position for opening said motor switch, and means whereby said motor switch is automatically closed when said finger piece is released.

5 10 15 20 25 30 35 23. In radio tuning apparatus, a remote control box containing a series of circularly arranged contacts which represent each a certain station, a rotary switch arm normally in a position where it can not engage said contacts, means whereby said arm is movable into engagement with any one of said contacts after the arm has been rotatably adjusted to select a station, said means including a manually operable member, a normally closed loudspeaker switch in said box, and means for holding said switch open as long as said arm engages one of said contacts, the manual release of said member instantly closing said switch and disengaging said arm from the selected contact, in combination with a radio receiver having adjustable tuning means and a loudspeaker, electric mechanism for operating said tuning means, operative connections between said mechanism and said contacts whereby the operation of said member to close said switch arm against a selected one of said contacts automatically causes said mechanism to adjust said tuning means for the selected station, and means for connecting said loudspeaker switch in the circuit of said loudspeaker, so that the latter remains inoperative as long as said manual member is held in operated position, the release of said member automatically rendering the loudspeaker operative.

40 45 50 55 60 65 70 75 24. In radio tuning apparatus, a remote control box containing a normally closed loudspeaker switch, a manually adjustable station-selecting member carried by said box, a plurality of electric contacts arranged to be selectively engaged by said member and representing each a certain station, said member being also adapted to occupy a universal tuning position independent of said contacts for selecting any station within the broadcasting range, means for automatically opening said switch when said member engages one of said contacts, means whereby said switch remains closed when said member is in said universal tuning position, and a normally open motor switch in said box adapted to be closed when said member is in engagement with any one of said contacts or in its universal tuning position, in combination with a radio receiver having adjustable tuning means and a loudspeaker, an electric motor for operating said tuning means, electric control mechanism between said motor and said tuning means to control the operation of the motor in accordance with a station selected by said member, operative connections between said mechanism and said contacts whereby the engagement of a selected contact by said manually adjustable member causes said mechanism to stop said motor when the tuning means is in position for the selected station, means for connecting said loudspeaker switch in the circuit of said loudspeaker, means for connecting said normally open motor switch in the circuit of said motor, which is thereby energized when said member is in operated position, and means for automatically rendering said control mechanism inoperative when said member is moved to universal tuning position.

25. In radio tuning apparatus, a remote control box containing a series of circularly ar- 75

ranged contacts which represent each a certain station, a spring switch arm mounted at one end for rotary movement and normally held out of engagement with said contacts, a finger piece attached to said arm near its free end for turning the arm and also pushing it toward said contacts, said box having an arcuate slot through which said finger piece extends, a second rotary switch arm movable with said first switch arm, and an arcuate contact member arranged to be engaged by the second arm in any rotatably adjusted position of the latter when said finger piece is pushed in, in combination with a radio receiver having adjustable tuning means, an electric motor for operating said tuning means, electric mechanism for controlling the operation of said motor, operative connections between said mechanism and said contacts whereby the operation of said finger piece to push said first-mentioned switch arm against a selected contact automatically causes said mechanism to stop said motor when the tuning means is in position for the selected station, and means for connecting said second switch arm and said arcuate contact member in the circuit 25 of said motor, which is automatically energized when said finger piece is pushed in.

26. The combination of a shaft adapted to rotate in opposite directions through a predetermined arc, a switch arm movable synchronously with said shaft, a series of contacts arranged to be engaged by said arm and representing certain preselected positions of said shaft, a single electric motor for operating said shaft in either direction, means for automatically reversing the rotation of said shaft at each end of its arc of travel, manually controlled means for selecting any position of said shaft, and means for automatically opening the motor circuit when said switch arm engages a contact which represents the selected position of said shaft.

27. The combination of a shaft adapted to rotate in opposite directions through a predetermined arc, rotary contact means operated synchronously with said shaft, a series of contacts arranged to be engaged by said contact means when the shaft is in certain preselected positions, a single electric motor for operating said shaft in either direction, means for automatically reversing the rotation of said shaft at each end of its arc of travel, a manually operated member for selecting any one of said positions of the shaft, and means conjointly controlled by said member and said contact means for opening the motor circuit when the shaft is in selected position.

28. In electric remote control apparatus, the combination of a rotary shaft adapted to occupy any one of a plurality of angular positions, a remote control device having a rotary knob which is also depressible like a push button, means whereby the manual release of said knob instantly restores it to normal position, a pointer movable with said knob over an index on which certain selected positions of said shaft are marked, normally open switches in said device representing the shaft positions noted on said index, said switches being selected for operation by the rotary movements of said knob, a single electric motor for operating said shaft in opposite directions through a predetermined arc, means whereby the pushing in of said knob sets the motor in operation until the selected position of said shaft is reached, means for automatically reversing the direction of rotation of said shaft at each end of its arc of travel, and means whereby the circuit 75 of said motor is automatically opened when said

shaft is in the angular position selected by said knob.

29. In radio tuning apparatus, a remote control box, a single rotary knob which is also depressible like a push button, means whereby the release of said knob instantly restores it to normal position, a pointer movable with said knob over an index on which certain selected stations are marked, normally open switches in said box representing the stations on said index, said switches being selected for operation by the rotary movements of said knob, in combination with a radio tuning shaft, a single electric motor for operating said shaft in opposite directions through a predetermined arc, means whereby the pushing in of said knob sets the motor in operation until the selected station is in tune, connections whereby the motor automatically stops when said shaft is in tuning position for a selected station, means operated by depressing the knob when in a certain rotatably adjusted position for closing the motor circuit independently of said switches, the motor circuit being interrupted when the knob is released, and means whereby the rotation of said shaft is automatically reversed at each end of its arc of travel while the knob is held depressed in said certain position, so that any broadcasting station can be tuned in by the operation of said single knob without regard to said index on the control box.

30. A radio receiver having adjustable tuning means, a loudspeaker, and an electric motor for operating said tuning means, in combination with a normally open switch in the motor circuit, a normally closed switch in the loudspeaker circuit, each switch including a movable member, and a single spring-pressed finger piece mechanically connected to both of said switch members for simultaneously actuating said members to close the motor switch and to open the loudspeaker circuit, whereby the loudspeaker is silent when said motor is energized to operate said tuning means, said spring-pressed finger piece when released returning automatically to normal position to open said motor switch and to close said loudspeaker switch.

31. Remotely tuned radio apparatus comprising the combination of a radio receiver having adjustable tuning means and a loudspeaker, an electric motor for operating said tuning means, a normally open switch and a normally closed switch located remotely from said receiver, means for connecting said normally open switch in the circuit of said motor, means for connecting said normally closed switch in the circuit of said loudspeaker, a single hand-operable member for closing the motor switch and at the same time opening the loudspeaker switch, the closing of said motor switch causing the electric motor to operate said tuning means to bring in a desired station, the opening of said loudspeaker switch causing the loudspeaker to remain silent during the tuning operation, and spring means for holding said member in normal position, whereby said loudspeaker switch is automatically closed upon manual release of said member to render the loudspeaker operative for the tuned-in station.

32. In electric remote control apparatus, the combination of a shaft rotatable to occupy any one of a plurality of predetermined angular positions, an electric motor for operating said shaft, a series of electric contacts remote from said shaft and representing each a different angular position of said shaft, a rotary switch arm normally spaced from all of said contacts and movable ax-

- ially into engagement with a selected contact, said switch arm when in normal position being radially adjustable into alignment with any one of said contacts, a normally open switch in the 5 circuit of said motor, a movable finger piece for closing said motor switch and axially moving the radially adjusted switch arm into engagement with a selected contact, means whereby said motor switch is closed by the operation of said finger piece irrespective of the radial position of said switch arm, spring means for normally holding said finger piece in circuit-opening position, whereby the release of said finger piece automatically returns said switch arm and said motor switch to open position, and electric mechanism associated with said shaft and operatively connected with said contacts and switch arm for automatically stopping said shaft in the angular position represented by the particular contact 10 15 20 25 30 35 40 45 50 55
- which said switch arm engages, said mechanism including a second switch in the motor circuit in series with said first motor switch, said second motor switch being normally closed, said control mechanism also including electromagnetic means automatically energized when said shaft is in pre-selected position to open the second motor switch, the automatic return of said switch arm to open position upon manual release of said finger piece causing said electromagnetic means to be de-energized and thereby close the second motor switch, the automatic opening of the first motor switch upon release of said finger piece holding the motor circuit open and thereby causing the shaft to remain in preselected angular position.
33. A radio receiver having a rotary tuning shaft, an electric motor for operating said shaft, and a loudspeaker, in combination with a remote control device having a single finger piece mounted to have a plurality of different operative movements, means for controlling said motor by certain movements of said finger piece, and means for controlling a circuit of said loudspeaker by other movements of said finger piece.
34. Remote-control apparatus for radio receivers, comprising a radio receiver having a rotary tuning shaft, an electric motor for operating said shaft, a loudspeaker, and electric control mechanism for said motor to stop said shaft in selected tuning position, said mechanism including a plurality of separately operable circuits representing each a selected station, in combination with a remote control box having a plurality of station-selecting contacts connected each to one of said circuits, a rotary hand knob on said box mounted also for limited axial movement in any rotatably adjusted position, spring means for normally holding said knob pushed out, contact means in said box normally out of engagement with said station-selecting contacts to hold said circuits open, whereby said knob is normally rotatable to station-selecting position without operating said control mechanism, the inward axial movement of said knob in station-selecting position automatically moving said contact means into engagement with the selected contact to close the corresponding circuit and thereby energize said electric control mechanism, which stops said shaft in selected tuning position, means for operatively connecting said loudspeaker with said box, and normally open switch means in said box adapted to be closed by the axial movement of said knob for energizing said tuning motor when the knob is pushed in in any radially adjusted position.
35. A radio receiver having a rotary tuning shaft, an electric motor for operating said shaft, and a loudspeaker, in combination with a remote control device having a rotary knob adjustable axially to two operative positions and rotatable in either axial position, means for controlling said motor by the rotary movements of said knob in one axial position, and means for controlling a circuit of said loudspeaker by the axial movements of said knob.
36. A radio receiver having an adjustable tuning shaft and mechanism for operating said shaft to any one of a plurality of preselected tuning positions, said mechanism including an electric motor for driving said shaft, in combination with a remote control box containing a plurality of normally open switches, which include contact members mounted in circularly spaced arrangement and representing certain stations, a rotary stem in said box mounted also for axial movement, a hand knob on the outer end of said stem to operate the latter, spring means for normally holding said knob in raised position, the depressed knob when released being at once restored to normal raised position by said spring means, a station indicator movable with said knob, which is freely rotatable in raised position to select any desired station, said circularly spaced switch members remaining all in open-circuit condition as long as the knob is in normal raised position, means carried by said stem for automatically closing a preselected switch when the knob is pushed in after being turned to select a station, and electric connections between said switches and said mechanism whereby the electric motor is automatically energized when the knob is pushed in to close a selected switch, said mechanism including means controlled by a closed switch for automatically stopping the tuning shaft in position for the station represented by the closed switch.

ADOLPH A. THOMAS.
